APPARATUS FOR REPRODUCING INFORMATION
FROM PHOTON-EMISSIVE STORAGE MEDIUMS
Robert W. Duwe, Minneapolis, Minn., assignor to Minnesota
Mining and Manufacturing Company, St. Paul,
Minn., a corporation of Delaware
Filed Mar. 18, 1964, Ser. No. 352,870
4 Claims. (Cl. 340—173)

This invention relates to a new and very useful apparatus for readout of information from photon-emissive, electron beam-sensitive recording media.

In one aspect, this invention relates to apparatus for serial readout of a recording medium having a differentially photon-emissive, electron beam-sensitive surface, the differential photon emission from such surface being representative of prerecorded input information.

While those skilled in the art have long understood that excited electrons cause photon emission from certain types of fluorescent materials, so far as is known to me no one has heretofore provided means for collecting a maximum amount of light emitted by a differentially fluorescent surface when struck by an electron beam of essentially constant intensity. By the present invention, a photon reflector positioned over a differentially photon emitting electron excited surface enables one to collect and reflect photon emission towards an appropriate photoelectric detection means so as to achieve superior readout of prerecorded information.

It is accordingly an object of the present invention to provide apparatus whereby a maximum amount of light emitted by a photon-emissive, electron beam-sensitive surface can be collected and used for readout of information.

Another object of this invention is to provide apparatus for serial readout of stored information from an electron beam-sensitive, photon emissive, sheet-like storage medium whereby such a medium is excitable by electrons to emit photons and such photon emission is collectable to a maximum possible extent and reflected (directed) towards photon sensitive detection means capable of continuously sensing the reflected photon emission.

A further object of this invention is to provide a combination of an electron beam producing means, a photon reflective means, and a photon sensitive detection means whereby serial readout of information from a differentially photon-emissive, electron beam-sensitive recording medium can be accomplished.

Other and further objects of this invention will become apparent to those skilled in the art from a reading of the attached specification, taken together with drawings, wherein:

FIGURE 1 is a diagrammatic sectional view of one embodiment of apparatus of this invention;

FIGURE 2 is an enlarged detailed sectional view of the region beyond the beam focusing coil rotated with respect to FIGURE 1;

FIGURE 3 is a front view of the photon reflector used in the embodiment of FIGURE 1 taken along the line 3—3 of FIGURE 2;

Background technology

Because those skilled in the art may not be familiar with the technology involved, a brief description of the prior art for purposes of this invention is now given:

A storage medium useful in the apparatus of this invention is sheet-like and initially has both:

(a) The capacity to alter selectively, chemically and internally its initial composition adjacent a surface thereof in response to exposure of that surface to differential irradiation, so that, either directly or as a result of subsequent processing (i.e. chemical and/or physical treatment) of such medium, such medium thereafter differentially radiates (i.e., transmits, absorbs, and/or emits) photon energy in a manner representative of the initial pattern of differential irradiation, and

(b) The capacity to emit photons uniformly from a surface thereof in response to uniform electron excitation of a surface thereof.

A specific example of a recording medium is as follows:

A two mil wet coating of the following homogeneous formulation is coated onto a 0.75 mil aluminum foil substrate and then dried:

2.0 gram zinc oxide (fluorescent material)

2.0 gram copolymer of 87 mol percent vinyl chloride and 13 mol percent vinyl acetate, 8.0 grams acetone (opacifiable material)

Using the resulting recording medium, recording is effected thereon in each of the following ways:

(a) A sample is scanned in a raster pattern under high vacuum with an intensity modulated electron beam of 20 kilovolts, 5 microampere peak target current in a 0.5×10^{-3} inch beam spot which scans out a 0.5 x 0.5 inch raster for times ranging from $\frac{1}{30}$ to 3 seconds.

(b) A sample is flooded with a non-scanning beam through an image-wise mask of total dimensions 0.5 x 0.5 inch with a 20 kilovolt, 5 microampere unmodulated electron beam for times ranging from $\frac{1}{30}$ to 3 seconds.

(c) A sample is exposed for 5 seconds to ultraviolet light by placing it 10 inches from an ultraviolet lamp, having the trade designation B-H6 as sold by the General Electric Company. Thereafter, each sample is heated to 150° C. until a black color is formed selectively in the irradiated area.

In each case the recorded information is retrievable by placing such sample in a vacuum chamber and scanning same with a focused beam of electrons to provide an image-wise differential photon emission from the sample surface. The photon emission is caused by fluorescence of the zinc oxide in the unexposed areas (the exposed areas being effectively masked). Simultaneously variations in the intensity of photon emission are detected with a photomultiplier. Owing to the fact that the photon emission from each sample in the foregoing illustration is emitted within a solid angle equal to the angle defined (i.e. subtended) by the media surface at the beam impact while the total angle occupied by the photon multiplier is but a small fraction of such solid angle, the photon emission collection efficiency of the photomultiplier is very inefficient. In the case where the recording medium being read out is planar with respect to the readout beam, the photon emission takes place within a solid angle ap-

oaching 2π steradians. If the recording medium is concavely curved towards the readout beam, the photon emission is emitted over a solid angle greater than about 2π steradians. If the recording medium is concavely curved with respect to the readout beam, then the photon emission takes place of a total solid angle less than about 2π steradians. It is by the apparatus of the present invention at one achieves a very useful and very efficient retrieval information stored in such a medium.

In storing information by such process, it is necessary to modulate the particular form of radiation to be used for storing so as to have the capacity to differentially or selectively irradiate a surface of a storage medium. Modulation can be effected by any conventional means whereby the characteristic of radiation to be used for storage of information is varied in such a manner or to such a degree that the resulting differential radiation is capable of producing photon-masking in the storage medium.

During a storing or recording operation, the irradiating with a differential radiation pattern of a surface of a storage medium results in chemically and internally selectively altering the initial composition of such medium adjacent at least one surface thereof. Such alteration results in the creation of a masking layer which is capable of differentially controlling the passage of photon energy therethrough in a manner representative of the initial pattern of differential irradiation.

The masking layer, which, while within a storage medium is adjacent one surface thereof, is in the nature of a image-wise recording of the input information with which the differential radiation is modulated. The input information recorded in the masking layer can be considered to comprise or to be in the form of a plurality of discrete resolution elements, each resolution element being considered to be the smallest piece or bit of information present. In amplitude each such bit is the smallest detectable signal level in a specified area of a recording medium, and in size it is the wave length of the highest spacial frequency within a specified area of a recording medium.

In general, retrieval is accomplished using uniform electron beam excitation of the previously irradiated storage medium. Thus, after storage and development (if necessary or desirable), a storage medium is placed in a vacuum chamber and one surface thereof is exposed to a field of excited electrons (e.g. an electron beam such as one generated by an electron gun).

When the resulting medium with its stored information is subsequently scanned with an unmodulated electron beam, the fluorescent material is excited sufficiently to emit photon energy material. As this photon energy passes through the photon masking layer, there results a difference in photon energy emission along the scan route between the differentially photon masked and unmasked areas. This difference in photon energy emission is detected photoelectrically. Photon energy detectors are well known and include such devices as photocells, photomultipliers, and the like.

Naturally, as in any storage and retrieval system involving a scanning operation, the resolution efficiency of retrieval when practicing the processes of this invention depends upon the relationship between unmodulated scanning beam size and the respective resolution elements comprising the stored input information in the masking layer of the recording medium. In order not to lose or fail to retrieve recorded information on readout, the relationship between the unmodulated scanning electron beam and each resolution element within a specified area of a storage medium surface should be such that the electron beam width measured in terms of the direction of relative velocity between the storage medium and the beam is not greater than the width of individual resolution elements to be read out (retrieved) measured in the same direction.

While the scanning electron beam used to excite the fluorescent material during retrieval is referred to as being

"unmodulated," those skilled in the art will appreciate that during the tracing of a raster by the beam in a scan field some sort of blanking may be employed during beam return for a new scan path in a raster pattern, for example one involving horizontal and vertical deflection, so that in this sense the beam is truly unmodulated only during its passage across a scan field. Furthermore, in certain situations, it may be desirable to impose upon the unmodulated portion of such beam pulsed signal information or the like, for example to cause particular effects upon, in, or about the recording or storage medium during readout. However, for retrieval purposes differential photon emission from the masking surface of the storage medium is achieved by an electron beam which is essentially uniform during residence time upon a storage medium. It will be appreciated that, as a consequence, the differential fluorescent pattern produced from the surface of such storage medium as a result of such uniform beam impact produces photon emission bearing information which need not be at all associated with or carried by the unmodulated scanning readout beam itself.

Apparatus description

Referring to the drawings, it will be seen that in the embodiment shown in FIGURES 1-3, the entire apparatus is enclosed in an envelope 9 which is adapted for evacuation and defines therewithin a generally elongated, generally cylindrically shaped cavity. As those skilled in the art will appreciate, and as will become more apparent from the subsequent description herein, this envelope need only enclose the portion of the apparatus which is to be traversed by the electron beam.

In FIGURE 1 there is seen an electron source, herein designated in its entirety by the numeral 10. Source 10 is adapted to emit along axis 11 within envelope 9 a beam of electrons 12 depicted in outline form. The electron source 10 is seen to comprise a filament or cathode 13, a grid 14 and an anode 15. The construction of electron sources is well known to those of ordinary skill in the art.

An electron beam optical system herein designated in its entirety by the numeral 17 is positioned generally in the middle portion of envelope 9. This system 17 is adapted to focus the beam 12. In the embodiment shown, the system employs one electromagnetic lens 18 which is axially aligned with the axis of beam 12 and one plate 19. Plate 19 has generally circular, centrally located aperture 21 therein which serves to limit and collimate beam 12.

The construction of electron optical systems or means is likewise well known to those of ordinary skill in the art. It will be appreciated that electrostatic as well as electromagnetic lenses can be used. One can employ more than one lens and a plurality of aperture plates for focusing and collimating an electron beam. Depending upon the cross-sectional size, shape, intensity, etc., of the beam needed, as well as the type of electron source used and the type of recording medium involved, those skilled in the art will appreciate that it is convenient to use any suitable combination of electron source and electron optical system.

Positioned in envelope 9, in axial alignment with beam 12 after or following that portion of the electron optical means or source 17 which is furthest removed from the electron source 10, a beam deflection means is provided. As shown in FIGURES 1 and 2, such beam deflection means is provided by an electromagnetic deflection yoke 20, which is positioned adjacent the lens 18. The yoke 20 is of conventional construction and, like any beam deflection means, is adapted to cause the beam 12 to move over predetermined portions of a scan field upon the face of platform 24 in a raster pattern (not shown). Platform 24 is located within the envelope 9 in proximity to the end thereof opposite that in which the electron source 10 is positioned. Lens 18 is chosen so as to have a suitably long focal length in order to

maintain a considerable distance between lens 18 and platform 24 and thereby accommodate yoke 20 and reflector 27.

It will be appreciated that embodiments can be constructed which do not employ beam deflection means. In these instances a relative velocity between the electron beam and the recorded information (i.e., the recording medium) can be provided by continuously moving the recorded information past (i.e., through) a stationary electron beam by some sort of conventional transport mechanism (not illustrated).

In order to position a prerecorded differentially photon-emissive, electron beam-sensitive recording medium 23 within the scan field upon the face of platform 24, some sort of positioning and/or supporting means is provided. As shown in FIGURES 1 and 2 such means comprises the platform 24 over which is passed discontinuously, or continuously, a photon-emissive, electron beam sensitive recording medium 23 which in this case is in tape or strip form. Movement of the medium 23 across platform 24 in front of beam 12 is provided by a conventional tape transport mechanism, herein designated in its entirety by the numeral 26. In some embodiments, the supporting means 24 and the mechanism 26 can be combined. While in the embodiment shown, the tape transport mechanism 26, the platform 24, and the medium 23, are positioned within the envelope 9, those skilled in the art will appreciate that alternative and equivalent arrangements can be conveniently used.

Positioned in envelope 9 between the yoke 20 and the platform 24 is a photon reflective means, here a circular reflector 27. This reflector 27 includes a spherically concave reflective surface 28 adapted to collect photon emission within a large solid angle approaching a maximum of about 2π steradians measured with respect to the surface of a flat medium 23 and the impinging beam 12. Naturally, if the surface of the medium is not flat, the available solid angle (the angle subtended by the medium) can be greater than 2π and the reflective surface can be designed to collect over a greater solid angle than 2π . This reflector 27 can be constructed of any conventional material, such as aluminum, silver, or the like, which is relatively stable and non-volatile under the vacuum conditions conventionally associated with electron beam operation. I found that aluminum is a particularly useful material for constructing reflectors 27; I polish its reflective surface to such a degree that it becomes an effective reflector of photon energy. In general, I prefer to use concave reflective surfaces 28 which are elliptically shaped, because the known optical properties associated with reflectors of such shape make it easier and preferable to concentrate and reflect from surface 28 towards a focal plane the photon emission received from a medium 23.

In order to permit the beam 12 to pass unimpeded to the scan field 22 through the reflector 27, reflector 27 is provided with a small aperture 32 whose location and dimensions are so chosen as to permit the beam to move over the entire scan field in a raster pattern without striking the reflector 27. In FIGURES 1 and 2, the reflector 27 and aperture 32 are constructed so that the axis 11 of beam 12 passes through the apex region of reflector 27. In general, the reflector 27 is positioned in envelope 9 after the electron optical system 17 (and yoke 20, if used) and before the supporting means 24. Those skilled in the art will appreciate that a number of different possible constructions can be used for the reflective means in place of the reflector 27; a few alternative constructions are hereinafter described. Also, such people will appreciate that the axis of reflector 27 can be angularly disposed with respect to the axis 11 of beam 12 as when it is desired to position the photoelectric device to one side of the medium 23. In general however, a reflective means is so positioned as not to impede or affect the path of the beam. Thus, the

reflective means is always so positioned or constructed as to be discontinuous at the path of the beam. In the embodiment of FIGURES 1 and 2, the aperture 32 provides the discontinuity in reflector 27. Naturally, it is preferred to keep the aperture 32 as small in its dimensions as conveniently possible in order to maximize the amount of photon emission which can be collected by the surface 28 of reflector 27, and reflected to the photon detector means (i.e., a photomultiplier 29). Similarly, which it is preferred to use reflective means capable of reflecting photon energy to a focal plane or point, it will be appreciated that for many purposes the focal plane can be poorly defined, if at all.

Positioned generally after the medium 23 with respect to the electron source 10 is a photon-detection means. Any conventional photon electric detection means can be used in the embodiments shown, including devices such as photocells, photo-multipliers, and the like. For example, as shown in FIGURES 1 and 2, such a means is a photo-multiplier 29 which converts photon energy input into an electrical signal output representative of the photon energy input. The photo-multiplier 29 is positioned in envelope 9 with respect to the reflector 27 and the medium 23 so as to be in a position to collect as much as possible (ideally all) of the photon rays 31, reflected from the surface 28 of reflector 27. The photo-multiplier 29, as a practical matter, can be positioned exactly at the image or focal plane (if one is definable) of the photon rays 31 or it can be positioned before or after such focal plane.

While the photon detection means as shown in the embodiments herein is positioned inside envelope 9, those skilled in the art will appreciate that in other embodiments such means can be positioned outside of such an envelope 9. Thus, a window or lens (not shown) can be positioned in the end of envelope 9. Then, the photo-multiplier 29 can be suitably positioned in front of such window outside envelope 9 and there used to sense the photon emission from medium 23 as reflected from reflector 27 at some point outside of the envelope 9. In general, the photon detection means is positioned after the supporting means with respect to the direction of beam movement and adapted continuously to sense photon energy reflected from the reflective means.

Those skilled in the art will appreciate that, while in the embodiments shown in the drawings the medium 23 is positioned generally normally to beam 12, there is nothing particularly critical in such an arrangement and indeed it is possible to position the medium 23 at an angle with respect to the beam 12. Similarly, it may be desirable to position the reflector 27 at such angle as to reflect photon emission from medium 23 towards photon detection means not axially aligned with beam axis 11. The exact angular interrelationship between medium 23 (or platform 24), reflector 27, beam 12 (or source 10), and photon detection means (like photo-multiplier 29) can obviously vary widely from one embodiment to another, as will readily be appreciated by those of ordinary skill in the art.

Concerning the relationship between the reflector 27 and the photo-multiplier 29 in FIGURES 1 and 2, it will be appreciated that, while it is generally convenient and even desirable to keep the photo-multiplier 29 behind and spaced at a short distance from the back of the medium 23, it is quite possible and convenient in some circumstances, depending upon the particular apparatus involved, the shape of the reflector surface 28, the type of photon sensitive detection means employed, the type of medium 23 employed, and other factors, to position the photo-multiplier 29 at a level or position such that the photo-multiplier 29 is approximately equivalent to or in lateral alignment with the surface of the recording medium 23. The photo-multiplier 29 is not positioned before or in front of the medium 23 because in such an arrangement the photo-multiplier 29 would interfere with the

oton emission from the medium 23 and to this extent 5 down upon the light collection efficiency of any arrangement involving reflector 27, medium 23, and photomultiplier 29.

It will be appreciated that the apparatus of this invention is particularly useful when one is reading out information stored in photon-emissive, electron beam-sensitive media which are substantially opaque to the emitted photons since the radiation from such media generally constitutes a point source, in radiation distribution causing only the 2π steradians on the electron beam struck 10 to be available for the detection solid angle when the media is flat at the position of beam impact. Indeed, in order to assure that no transmission of electron energy 15 photon energy through a medium will occur, it is desirable in many instances to position an opaque platform 1 back of the medium 23 as has been done in the embodiment shown in FIGURES 1-3 so as to assure no false readouts or collections of photon emission.

In the embodiment shown in FIGURES 1-3, together with the yoke 20 and the transport mechanism 26 comprise means for relatively moving beam 12 over predetermined portions of the differentially photon-emissive surface of medium 23. While the embodiment employs a medium 23 in tape form, it will be appreciated that the apparatus of this invention can also be used with media in sheet form. When using sheet-like media, an appropriate conventional sheet or card advancement mechanism (not shown) can be employed in place of transport mechanism 26. Of course, one can manually place a medium 23 on platform 24 and not use either a tape transport mechanism or a card advancement mechanism. However, apparatus of this invention requires some means for relatively moving beam 12 over medium 23, so that if no such mechanism is employed then it is usually convenient to employ yoke 20 or equivalent beam deflection means.

Also in the embodiment shown in FIGURES 1-3, together with the source 10 and the electron optical system 17 comprise electron beam producing means. Such means needs to be capable of producing an electron beam 12 having a width measured in the direction of relative velocity between beam 12 and medium 23 which is not greater than the width of individual resolution elements (not shown) associated with said medium 23 measured in the same direction.

Photomultiplier 29 is positioned to receive photon energy reflected from reflector means 27. The photomultiplier 29 is adapted to continuously sense the differential photon energy emitted by the medium 23 to produce an electric signal output generally corresponding to the rerecorded input information on medium 23. The photomultiplier 29 senses photon energy reflected from reflector 27 at a rate not less than that at which differences in photon emission from the beam-struck surface of medium 23 occur during relative movement of beam 12 to medium 23. Such differences in photon emission correspond to individual resolution elements in the recorded information, as indicated above.

Alternative embodiments

In FIGURES 4-10 are shown alternative embodiments of apparatus of this invention or portions thereof. Unless otherwise indicated, the elements in each of these respective figures are numbered the same as those in FIGURES 1-3 except that prime marks are added thereto for distinguishing purposes.

In FIGURE 4, there is seen an alternative embodiment wherein the deflection yoke and the reflector are one composite structure herein designated in its entirety by the numeral 33. The reflector-yoke structure 33 has a concave reflective surface 34 formed in its end portion remote from the source (not shown). Structure 33 is advantageously compact.

FIGURE 5 discloses a portion of another alternative embodiment wherein a photocell 36 is positioned outside a vacuum enclosure 37. An electron beam 38 is shown

passing through a magnetic deflection yoke 39 and impinging on a prerecorded medium 41. The consequent photon emission, shown as rays 42, is reflected by a reflector 43 (constructed similarly to reflector 27) through a photon transmissive window 44 of glass or the like to photocell 36. Window 44 is mounted across an aperture 46 in enclosure 37 by means of a conventional O-ring seal 47 and threaded cap 48 which together seal the photon transmissive window 44 to enclosure 37. The entire conventional transport mechanism 49 is shown housed within enclosure 37.

In FIGURE 6 is shown a further alternative embodiment wherein an electron beam 51 strikes a prerecorded medium 52 and produces photon emission as rays 53. Rays 53 leave medium 52 and strike, respectively, reflectors 54 and 56 at various angles, from which they are reflected onto respectively, photomultipliers 57 and 58. The entire assembly is housed within an enclosure 59. Medium 52 is opaque and stationary during scanning by beam 51, which is deflected in a horizontal pattern by yoke 61. This configuration of apparatus elements provides two individual detectable images and greater reliability of signal detection for high resolution readout of high density information storage, for example. When image production from recorded information is desired, this arrangement is sometimes less desirable than others described herein because of photon aberration and image astigmatism. If more than two separate detectable images are desired, additional reflectors may be incorporated into the arrangement, space and configuration, parameters permitting.

In FIGURES 7 and 8 (FIGURE 8 is reduced 25% due to space limitations) is illustrated an alternative reflector construction and diagrammatically a manner of using the same. Here, an electron beam 62 after passing through an aperture 60 of reflector 68 impinges upon a prerecorded medium 63 generating rays 64, 65, and 66, among others (not shown). These rays 64, 65, and 66 strike the reflective surface 67 of reflector 68. Owing to the shape of surface 67 (shown generally in FIGURE 7 as a diametrical, vertical section), rays 64 and 66 which emit from medium 63 in respective directions closely parallel to but in an opposite direction from, beam 62, strike surface 67 and are directed laterally, radially and outwardly from the reflector axis (which in FIGURE 7 is coincident with beam axis 62). After next striking surface 67, the rays 64 and 66 are reflected outwardly to photomultiplier 69 in the direction of beam 62 movement. Ray 65 which leaves medium 63 at an acute angle is reflected diametrically across surface 67 after impact thereagainst, to be finally reflected outwardly to photomultiplier 69. The surface 67 of reflector 68 is so shaped as not only to have the usual properties of an elliptical reflector but also to have the capacity to collect rays emitted substantially along or towards the axis of beam 62, which rays would otherwise represent lost energy, since they would otherwise reflect back towards medium 63 after reflection from mirror having a conventional elliptically reflective surface. Naturally, the shape of the surface 67 of reflector 68 must be carefully formed for optimum results.

In FIGURES 9 and 10 is shown one additional reflector construction suitable for use in apparatus of this invention. Here the reflector comprises a pair of spherical segments 70 and 71, respectively, each positioned with respect to one another and to the axis 72 of a beam 73 approximately as suggested in FIGURES 9 and 10. FIGURE 9 can be considered to be a vertical, sectional view taken along the line 9-9 of FIGURE 10.

In all embodiments, the photoelectric detection means is so positioned as to have reflected photon energy strike its photo-sensitive portions.

Having described my invention, I claim:

1. Apparatus for serial readout of a recording medium having a differentially photon-emissive, electron beam-sensitive surface, the differential photon emission from

such surface being representative of prerecorded input information, said apparatus comprising:

- (a) a supporting envelope adapted for evacuation defining therewithin a generally elongated cavity,
  - (b) electron beam producing means positioned in said envelope and adapted to emit generally lengthwise within said envelope a substantially uniform electron beam,
  - (c) means for supporting a differentially photon-emissive, electron beam-sensitive recording medium in the path of said electron beam, the differentially photon emissive areas associated with a said recording medium being resolvable into a plurality of discrete resolution elements,
  - (d) means for relatively moving said electron beam over predetermined portions of a said recording medium when a said medium is so supported,
  - (e) said electron beam having during such relative movement a maximum width measured in the direction of relative velocity between said electron beam and a said recording medium not greater than the width of individual resolution elements to be read out associated with a said medium measured in the same direction,
  - (f) photon reflective means positioned in said envelope between said electron beam producing means and said supporting means, said photon reflective means being discontinuous across the path of said beam,
  - (g) said reflective means including a concave reflective surface adapted both to collect photon energy emitted from the beam-struck surface of such a recording medium within a solid angle not larger than that solid angle subtended by said recording medium at the impact situs of said beam on such beam-struck surface and to reflect such energy in a direction generally away from said electron source, and
  - (h) photoelectric detection means positioned to receive photon energy reflected from said reflective means and adapted to continuously sense the differential in said photon energy emitted and produce an electric signal output generally representative of said prerecorded input information on a said medium.
2. Apparatus for serial readout of a recording medium having a differentially photon-emissive, electron beam-sensitive surface, the differential photon emission from such surface being representative of prerecorded input information, said apparatus comprising:
- (a) a supporting envelope adapted for evacuation defining therewithin a generally elongated, generally cylindrically-shaped cavity,
  - (b) an electron source positioned in one end of said envelope and adapted to emit generally axially within said envelope a substantially uniform beam of electrons, said source including a filament, a grid, and an anode,
  - (c) electron optical means positioned generally in the middle portion of said envelope and adapted to focus said beam in a scan field defined across said beam axis within said envelope in proximity to the opposite end thereof,
  - (d) beam deflection means positioned in said envelope in axial alignment with said beam following that portion of said electron optical means furthest removed from said electron source and adapted to cause said beam to move over predetermined portions of said scan field in a raster pattern,
  - (e) means for supporting a differentially photon-emissive, electron beam-sensitive recording medium in the path of said electron beam, the differentially photon emissive areas associated with a said recording medium being resolvable into a plurality of discrete resolution elements,
  - (f) means for relatively moving said electron beam over predetermined portions of a said recording medium when a said medium is so supported,

- (g) said electron beam having during such relative movement a maximum width measured in the direction of relative velocity between said electron beam and a said recording medium not greater than the width of individual resolution elements to be read out associated with a said medium measured in the same direction.
- (h) photon reflective means positioned in said envelope between said electron beam producing means and said supporting means, said photon reflective means being discontinuous across the path of said beam,
- (i) said reflective means including a concave reflective surface adapted both to collect photon energy emitted from the beam-struck surface of such a recording medium within a solid angle approaching that solid angle subtended by said recording medium at the impact situs of said beam on such beam-struck surface and to reflect such energy in a direction generally away from said electron source, and
- (j) photoelectric detection means positioned to receive photon energy reflected from said reflective means and adapted to continuously sense the differential in said photon energy emitted and produce an electric signal output generally representative of said prerecorded input information on a said medium.

3. Apparatus for serial readout of a recording medium having a differentially photon-emissive, electron beam-sensitive surface, the differential photon emission from such surface being representative of prerecorded input information, said apparatus comprising:

- (a) a supporting envelope adapted for evacuation defining therewithin a generally elongated, generally cylindrically-shaped cavity,
- (b) an electron source positioned in one end of said envelope and adapted to emit generally axially within said envelope a substantially uniform beam of electrons, said source including a filament, a grid, and an anode,
- (c) electron optical means positioned generally in the middle portion of said envelope and adapted to focus said beam in a scan field defined across said beam axis within said envelope in proximity to the opposite end thereof,
- (d) beam deflection means positioned in said envelope in axial alignment with said beam following that portion of said electron optical means furthest removed from said electron source and adapted to cause said beam to move over predetermined portions of said scan field in a raster pattern,
- (e) means for supporting a differentially photon-emissive, electron beam-sensitive recording medium in said envelope in the path of said electron beam, the differentially photon emissive areas associated with a said recording medium being resolvable into a plurality of discrete resolution elements,
- (f) means for relatively moving said electron beam over predetermined portions of a said recording medium when a said medium is so supported,
- (g) said electron beam having during such relative movement a maximum width measured in the direction of relative velocity between said electron beam and a said recording medium not greater than the width of individual resolution elements to be read out associated with a said medium measured in the same direction.
- (h) said envelope having defined in its opposite end portion a photon transmissive window,
- (i) photon reflective means positioned in said envelope between said electron beam producing means and said supporting means, said photon reflective means being discontinuous across the path of said beam,
- (j) said reflective means including a concave reflective surface adapted both to collect photon energy emitted from the beam-struck surface of such a recording

11

medium within a solid angle approaching a 2π steradians over the impact situs of said beam on such beam-struck surface and to reflect such energy in a direction generally away from said electron source, and

(k) photoelectric detection means positioned outside of said envelope adjacent said window so as to receive photon energy reflected from said reflective means and adapted to continuously sense the differential in said photon energy emitted and produce an electric signal output generally representative of said prerecorded input information on a said medium.

4. Apparatus for electronically retrieving prerecorded information from a recording medium having a differentially photon-emissive, electron beam responsive surface, 15 a differential photon emission from such surface being representative of prerecorded input information, said apparatus comprising in combination:

(a) means for generating and for relatively moving a substantially uniform electron beam over predetermined portions of a said recording medium, said electron beam having during such relative movement thereof a maximum width measured in the direction of relative velocity between said electron beam and said medium not greater than the width of individual 20

5

resolution elements to be read out associated with said medium measured in the same direction,

(b) means for collecting photon energy emitted from the so beam-struck surface of said medium within a solid angle not larger than that solid angle subtended by said medium at the impact situs of said beam on such beam-struck surface and for reflecting such energy in a direction generally away from said electron source, and

(c) means for sensing photon energy from said means for collecting and reflecting and for converting such energy into a corresponding electric signal output, thereby to electronically retrieve prerecorded information from said medium.
